UNITED STATES PATENT OFFICE.

JOHN GRUNWALD, OF PHILADELPHIA, PENNSYLVANIA.

TROUSERS SUPPORT.

Application filed May 2, 1927. Serial No. 188,066.

My invention relates to trouser supports and more particularly to the clasps forming parts thereof.

The principal object of this invention is to provide an improved clasp whose clamping parts may rotate relative to one another and be readily locked in fixed position.

Another object is to provide a clasp which may be used in conjunction with an elastic band for forming an improved trouser support which is neat and attractive in appearance.

These objects, and other advantageous ends which will appear hereinafter, I attain in the following manner, reference being had to the accompanying drawings in which:

Figure 1 is an elevation of a trouser support, the clasp of which embody part of my invention, and

Figure 2 a fragmentary perspective view of a pair of trousers to which a pair of the supports shown in Figure 1 are attached.

Figure 3 is a top plan view of a clasp embodying part of my invention,

Figure 4 an outside elevation of same, and

Figure 5 an edge view taken substantially on line 5—5 on Figure 4.

Figure 6 is a perspective view of the rear part of the clasp shown in Figure 3, and

Figure 7 an enlarged cross-sectional view, taken substantially on line 7—7 on Figure 3, a portion of the rear part of the clasp being broken away.

Referring now more particularly to Figures 3 to 7, the clasp is provided with a rear part 10 having an elongated aperture 11 formed therein, an offset notched lower end 12, and a hinge part 13 which is provided with a shoulder 14. A front part 15, which may be finished in any desired manner and provided with an emblem or other device, has a hinge part 16 secured to its upper edge and provided with a shoulder 17 adapted to co-act with the shoulder 14 formed on part 10.

Both parts 10 and 15 are bored to receive a shaft 18 and front part 15 has a counterbore 19 adapted to receive a coiled spring 20 which encircles shaft 18 and bears against the bottom of counterbore 19 and a hub 21 formed on shaft 18, the outer end of which is enlarged to form a knob 22.

A key 23 is fixed on hub 21 and adapted to engage a notch 24 when hub 21 is rotated, as will hereinafter be described, and a flange

25 is formed on the other end of shaft 18 in order to prevent same from moving transversely of hinge part 13; the distance between flange 25 and key 23 being equal to 60 the sum of the lengths of hinge parts 13 and 16 so that shoulders 14 and 17 are prevented from moving out of engagement with one another.

As spring 20 bears against the bottom of counterbore 19 and against hub 21, it tends to move shaft 18 transversely of front part 15, however, flange 25 prevents a shaft 18 from moving transversely of rear part 10 and consequently hinge part 13 is pressed 70 into engagement with the end of hinge part 16 and thus holds shoulder 14 in engagement with shoulder 17. By rotating knob 22 until key 23 is out of alignment with notch 24, key 23 will bear against the end of hinge 75 part 16 and hold shoulders 14 and 17 rigidly together. By rotating knob 22 until key 23 aligns with notch 24, shaft 18 may be moved transversely of hinge part 16, against the action of spring 20, and allow shoulders 14 80 and 17 to separate so that rear part 10 and front part 15 may be rotated on shaft 18 independently of one another.

Referring now to all the views simultaneously, two clasps 26, illustrated in Figures 3 85 to 7, and two clasps 26^a, are shown attached to the waist band 27 of a pair of trousers and connected to one another by an elastic band 38; the ends of which are inserted through aperture 11, folded back on the body 90 of the band and stitched as shown in Figure 2. Lower end 12 of rear part 10 is offset primarily to compensate for the thickness of band 28 so that the teeth formed by the notches in lower end 12 may engage the inner side of waist band 27.

In attaching clasp 26 to the waist band of a pair of trousers, knob 22 is rotated until key 23 aligns with notch 24 and is then pressed inwardly so that rear part 10 may be 100 swung away from front part 15. The clasp is then placed over the trouser band and the front and rear parts pressed toward one another so that shoulder 14 may align with shoulder 17; at which time spring 20 will 105 draw hinge part 13 toward hinge part 16 and the shoulders will interlock and prevent the front and rear parts of the clasp from swinging away from one another. Knob 22 is then rotated so that key 23 will bear 110 against the end of hinge part 16 and securely lock shoulders 14 and 17 in engagement with

one another. Clasp 26^a is attached to the waist band of the trousers in the same manner after stretching elastic band 28 sufficiently to cause the waist band of the trousers to fit snugly to the body of the wearer.

In order that band 28 may be held in its proper position relative to the top of the trouser band, I provide a clasp 29 which is similar to clasp 26 with the exception that 10 its front part 30 is substantially smaller than front part 15, and its rear part 31 is substantially smaller than rear part 10 and is provided with apertures so that it may be stitched to band 28. The only function of 15 clasp 29 is to keep elastic band 28 and the waist band 27 in alignment, and it is not intended that it shall grip the trousers, but merely to ride on the top of the waist band.

While I have illustrated and described a 20 preferred embodiment of my invention, it will be readily understood that modifications may be made without departing from the spirit thereof, and hence I do not limit myself to the precise construction set forth, but 25 consider that I am at liberty to make such changes and alterations as fairly come within the scope of the appended claims.

I claim:—

1. A clasp including a shaft, hinged parts 30 on the shaft, shoulders on the hinged parts engaging one another and separable by moving one part longitudinally of the shaft relatively to the other part, and means for yield-

ingly holding the shoulders in engagement with one another.

35

2. A clasp including a shaft, hinged parts on the shaft, shoulders on the hinged parts engaging one another and separable by moving one part longitudinally of the shaft relatively to the other part, and means for locking the shoulders in engagement with one another.

40

3. In a trouser support, a clasp having a shaft, a rear part hinged on the shaft, a counterbored front part hinged on the shaft, shoulders formed on the front and rear parts, a hub on the shaft, and a spring engaging the hub and the inner end of the counterbore whereby the shoulders are resiliently held in engagement with one another.

45

4. In a trouser support; a clasp having a shaft; a rear part hinged on the shaft; a front part, having a counterbore and a keyway, hinged on the shaft; shoulders formed on the front and rear parts; a hub on the 50 shaft; a spring in the counterbore and engaging the hub and the inner end of the counterbore; a key on the hub for locking the shoulders in engagement with one another and adapted to be inserted into the keyway 55 against the action of the spring whereby said shoulders may be separated.

55

In testimony whereof I have signed my name to this specification.

JOHN GRUNWALD.
